[57] CLAIM

The ornamental design for a vertical hanging file, as shown and described.

DESCRIPTION

FIG. 1 is a left front perspective view of a vertical hanging file showing my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view, the left side being a mirror image thereof; and

FIG. 7 is a cross-sectional view thereof taken in the direction of arrows 7—7 in FIG. 4.

FIG. 2

FIG. 3

FIG. 4

FIG. 5

FIG. 6

FIG. 7
